UNITED STATES PATENT OFFICE.

EDGAR A. EDWARDS, OF CINCINNATI, OHIO, ASSIGNOR, BY MESNE ASSIGNMENTS, TO METROPOLITAN TRUST & SAVINGS BANK, TRUSTEE, A CORPORATION OF ILLINOIS.

SIGNAL-LIGHT.

SPECIFICATION forming part of Letters Patent No. 787,740, dated April 18, 1905.

Application filed November 25, 1901. Serial No. 83,534.

To all whom it may concern:

Be it known that I, EDGAR A. EDWARDS, a citizen of the United States, residing at Cincinnati, in the county of Hamilton and State of Ohio, have invented certain new and useful improvements in Signal-Lights, of which the following is a specification.

My invention relates to that class of railway-signals combined with locomotive-head-lights set forth in Letters Patent to Samuel H. Harrington, No. 495,938, dated April 18, 1893; and my invention consists of a certain improved arrangement of the supplemental reflector, as fully set forth hereinafter and as illustrated in the accompanying drawings, in which—

Figure 1 is a sectional elevation of sufficient of a locomotive-headlight to illustrate my invention, and Fig. 2 is a plan view.

The casing A and concave reflector C and lamp B of the headlight are of any usual or suitable construction. Within the reflector C is arranged a supplemental reflector E, and this reflector E is so set that a portion of the rays from the lamp falls upon the same and is reflected upward, and to permit them to pass upward to constitute a signal of the proper character the reflector C is cut away, forming an opening y, and the casing A is cut away, forming an opening w, which preferably is closed by a glass plate a, so as to prevent the entrance of rain and snow.

The reflector E may be set permanently in its angular position to throw the light-rays upward, and it may be curved so as to secure the parallelism of these rays when necessary; but for signaling purposes, in order that it may be known that the engine is in motion, it is preferable to so support the reflector E that it will be vibrated or rotated rapidly from the action of the engine itself—as, for instance,

by means of the belts and pulleys deriving their motions from one of the rotating shafts t of the engine, as shown in Fig. 1.

When the reflector E is a flat plate, as shown, it will offer but little obstruction to the light-rays when it occupies a longitudinal position, as shown in full lines, and will reflect a portion of the rays directly upward when carried to the angular position. (Shown in dotted lines.)

The reflector E may be made of any suitable material—as, for instance, a metallic plate with polished surfaces, or it may be of transparent material, as a plate of glass, in which case a portion of the light-rays will pass through this plate and another portion will be reflected. I do not, however, claim, broadly, the combination, with a locomotive-headlight, of a reflector of transparent material, as this is the subject of a separate application for Letters Patent, Serial No. 84,277, filed November 30, 1901, in which, however, the reflector is stationary and in some cases outside the case.

Without limiting myself to the specific construction and arrangement of parts shown, I claim as my invention—

The combination with the casing and stationary concave reflector C, having openings for the passage upward of light-rays, of a supplemental reflector within the reflector C, and means for rotating the supplemental reflector, substantially as set forth.

In testimony whereof I have signed my name to this specification in the presence of two subscribing witnesses.

EDGAR A. EDWARDS.
